SPRAYING DEVICE

Raymond R. Ward, Brecksville, and Harold A. Waters, Cleveland Heights, Ohio, assignors to The Sherwin Williams Company, Cleveland, Ohio, a corporation of Ohio

Application December 29, 1947, Serial No. 143,426

Term of patent 14 years

(Cl. D35—2)

To all whom it may concern:

Be it known that we, Raymond R. Ward and Harold A. Waters, citizens of the United States, residing at Brecksville and Cleveland Heights, respectively, both in the county of Cuyahoga and State of Ohio, have invented a new, original, and ornamental Design for a Spraying Device, of which the following is a specification, reference being had to the accompanying drawings, forming a part thereof.

Fig. 1 is a side view of a spraying device, showing our new design. The broken lines showing the container are for illustrative purposes only;

Fig. 2 is an elevational view taken from the opposite side on an enlarged scale with a portion of the tubular member broken away;

Fig. 3 is a fragmentary view of the nozzle portion of the device;

Fig. 4 is a perspective view of the nozzle portion of the device;

Fig. 5 is a sectional view taken on the lines 5—5 of Fig. 2; and

Fig. 6 is a sectional view taken on lines 6—6 of Fig. 2.

We claim:

The ornamental design for a spraying device, as shown and described.

RAYMOND R. WARD.
